(57) **CLAIM**

We claim the ornamental design for a modular will-call storage device, as shown and described.

DESCRIPTION

FIG. 1 is a front, right, perspective view of a modular will-call storage device showing our design;

FIG. 2 is a back, left, perspective view thereof;

FIG. 3 is a top plan view thereof;

FIG. 4 is a right side elevational view thereof, the left side elevational view being a mirror image thereof; and,

FIG. 5 is a front elevational view thereof at a reduced scale and shown joined together with a plurality of said modular will-call storage devices in broken lines.

The broken lines are for illustrative purpose only and form no part of the claimed design.
